UNITED STATES PATENT OFFICE.

ARTHUR DULTGEN, OF NEW YORK, AND ADOLPH WEISS, OF BROOKLYN, NEW YORK.

MACHINE FOR OBTAINING THE REGISTER OF THE ETCHINGS FOR MULTICOLOR INTAGLIO PRINTING CYLINDERS.

Application filed December 8, 1925 Serial No. 74,034.

This invention relates to a machine for obtaining the register of the etchings for multicolor intaglio printing cylinders.

In the present state of the art the machines used for producing register in etchings for multicolor intaglio printing cylinders, are dependent on manual skill, resulting very often in deficient results. In the machines heretofore used if only one of the etchings on one cylinder is located out of register, with the coating etchings on the other cylinders, the error is only discovered after the cylinder has been etched and placed in the printing machine, and no means are provided for checking up the locations of the etchings until after the operation of etching, necessitating the remaking of the whole cylinder. This will cause considerable financial loss and delay.

In this art it is known that carbon tissue, as used for producing etchings on intaglio printing cylinders, tends to distort, due to the influence of atmospheric conditions, and causes the etchings produced to be out of register, even if the carbon tissue has been accurately located on the register marks of the cylinder. The amount of distortion is aggravated with the increase in size of the carbon tissue used.

The object of this invention is the elimination of human skill, in correctly locating the register marks on the various color cylinders used, for intaglio multicolor printing, and substituting therefor mechanical means. The second object of the invention is the elimination of the risk of misplacing the register marks on the printing cylinders. The third object of the invention is the provision of means to check up the accuracy of the transfer of the register marks, on what we term a key color cylinder, to a plurality of receiving cylinders before attaching the carbon tissues to the latter. The fourth object of the invention provides means for correcting the location of a carbon tissue on a receiving cylinder, before etching. The fifth object of the invention

provides means, for using carbon tissues of small sizes to reduce the distortions, due to atmospheric influences. The sixth object of the invention has for its object the reduction of the time required, to produce multicolor intaglio printing cylinders, allowing quick, easy and sure means of transferring register marks and locating and developing carbon tissues on the printing cylinders. The seventh

object of the invention is the production of means to etch flat tints on a color cylinder, from border lines transferred from an etched cylinder, using only a screened carbon tissue, saving all photographic labor and material, and to determine the correct position for the same on the printing cylinder. The eighth object of the invention is the production of means to etch pictures on a color cylinder from a printed transfer, obtained from an etched key color cylinder, using the ink film obtained by the transfer, as an acid resist, using only a screened carbon tissue, saving thereby all photographic labor, and material, and also locating the correct position of the picture on the printing cylinder. The ninth object of the invention is the production of automatic means, to indicate inaccuracies in the size of the printing cylinders, which if not detected will result in trouble, during the printing operation and throw the pictures out of register, requiring the remarking of the printing cylinder, causing a waste of time, labor and material, in the preparation and etching of the cylinder and cause a delay of time in the printing operation.

In the accompanying drawings Fig. 1 represents an outside front elevation of an exemplification of the multicolor registering machine; Fig. 2 shows an outside rear elevation of the machine; Fig. 3 indicates a top plan view of the machine; Fig. 4 represents a section of Fig. 3 on the line 4, 4; Fig. 5 shows a section of Fig. 1 on the line 5, 5; Fig. 6 indicates a section of Fig. 1 on the line 6, 6; Fig. 7 represents an elevation of some details; Fig. 8 is a top plan view of Fig. 7; Fig. 9 represents a left hand side view of a fragmentary portion of Fig. 3; Fig. 10 indicates a left hand side view of Fig. 9; Fig. 11 represents a top plan view of Fig. 9; Fig. 12 shows an enlarged partial section of Fig. 1 on the line 12, 12; Fig. 13 indicates a section of Fig. 12 on the line 13, 13.

The multicolor registering machine comprises the main front frame 20 and the main rear frame 21, which are tied together by the rods 22 and 23. Each of the said frames has extending therefrom a projection 25. On the inner face of each of the said frames 20 and 21 are formed the guide strips 26, which extend up to the upper ends of the projections 25. Corresponding strengthening ribs 27 ex-

tend from the outer faces of the frames 20 and 21. Each of the said frames has formed therewith the top flanges 30 which incline toward their outer ends, and terminate in 5 the journal bearings 31 and 32. Each of the top flanges 30 has formed therein the concaved clearance depressions 33. Flanges 34 are formed with the bottom ends of the frames 20 and 21. Side flanges 35 of each 10 frame extend between the ends of the flanges 34 and the journal bearings 31 and 32.

From the inner face of each of the frames 20 and 21 extend the guide strips 38, which are provided with the detachable guide 15 plates 39.

The top portion of the frame 20 has extending therethrough two pairs of similar journal pins 44, which support the rollers 46. Ball bearings may be provided for the rollers 46.

20 A shaft 50 has its ends journaled in the frames 20 and 21. Similar arms 51 and 52 have one end each fastened to the shaft 50 on the outer face of each of the frames 20 and 21. To the upper end of the arm 51 is pinned one end of the link 53, by means of the pin 54. A similar pin 55 extends from the upper end of the arm 52. A journal pin 56 extends from the frame 20 and has supported thereon one end of the handle 57. The link 53 has one end thereof pinned to said handle 57, by means of the pin 58. Intermediate similar arms 59 have also each one end thereof fastened to the shaft 50, adjacent to the inside faces of the frames 20 35 and 21. At the upper end of each of the arms 59 is formed an elongated housing 60. Two pairs of pins 61, extend from the inside face of each of the frames 20 and 21, each pair being disposed equidistant from the vertical 40 plane extending through the longitudinal center of the machine. Rollers 68 are supported on the pins 61 and may be provided with ball bearings. Straps 69 have their ends supported on the pins 61. Lifting bars 70 45 are guided between the rollers 68 and each has formed in its upper edge the recess 71 and retaining heel 72. One end of each bar 70 has extending therethrough a pin 73 on which is supported a roller 74, which latter 50 may be provided with ball bearings. The roller 74 is located in the elongated housing 60. On the pins 54 and 55 are each supported the rollers 78 which may be provided with ball bearings.

55 A shaft 82 is journaled in bearings formed in the frames 20 and 21. A pulley 83 is fastened to the shaft 82. A pair of cam discs 86 each with the cam projection 87 are fastened to the shaft 82. A spur gear 88 is also 60 fastened to the shaft 82. A journal pin 90 extends from the frame 20 and has journaled thereon the pinion 91. The pinion 91 meshes with the spur gear 88. A pin 92 extends from the frame 21 and has journaled thereon the pinion 93. A hand wheel 93^a is fastened to

the pinion 93. A shaft 94 is journaled in the frames 20 and 21 and has fastened thereto the pinion 95. The pinion 91 meshes with the pinion 95. A pinion 96 on the shaft 94 meshes with the pinion 93.

70 The ratchet wheel 97 is fastened to the shaft 94 adjacent to the pinion 95 and a pin 98 extends from each end of the shaft 94. A pin 105 extends from the frame 20 and has sleeved thereon the pawl with its tooth 107, 75 and its counterweight 108. The tooth 107 is adapted to lock with the teeth of the ratchet wheel 97. A detachable operating handle 109 is indicated with its hub end 110, which is adapted to coact with the pin 98 on the 80 shaft 94.

An adjustable bearing frame is designated in its entirety by the numeral 115. The frame 115 has formed in its vertical axial center line the similar bearings 116 and 117, 85 by means of which it is slidably supported on the rods 22 and 23. A screw 120 is indicated with the shank 121 and is in threaded engagement with the frame 115, which shank 121 is journaled in a bearing in the end frame 21. 90 An operating hand wheel 122 is fastened to the shank 121 adjacent to the outer face of the end frame 21. Two pairs of pins 126 are fastened to and extend through the frame 115. On each of the pins 126 is journaled a 95 roller 128, which may be provided with ball bearings. A pin 132 is supported in the frame 115, and in turn has supported thereon the lug 133 of the loading bar 135. A pair of journal lugs 136 extend from the lower 100 face of the loading bar 135, and have fastened thereto the journal pin 137 on which is journaled the roller 138, for which latter ball bearings may be provided. A pin 140 similar to 132 is fastened to and extends from the 105 frame 115. A lug 141 similar to 133 is supported on the pin 140 and is integral with the second loading bar 142, oppositely positioned to and similar to the loading bar 135. A pair of journal lugs 143 similar to 136 extend from the lower face of the loading bar 142, and have fastened thereto the journal 110 pin 144. On the latter is journaled the roller 145 similar to 138. A pair of loading bars similar to those already described are shown 115 at 146 and 146^a. Pins 147 similar to 140 extend from the frame 20 and support each one end of the latter loading bars. A roller 148 is journaled to the bar 146 and a roller 148^a is journaled to the bar 146^a. Removable 120 stop pins 149 are provided for openings 149^a, 149^b, 149^c and 149^d in each of the loading bars.

Similar cam shafts 150 and 151 are journaled in the frames 20 and 21. Cams 152 and 153 are respectively fastened to one end of the 125 said cam shafts, outside of the frame 20. Similar splines 154 are provided for each of the cam shafts 150 and 151. Cams 155 and 156 similar to the cams 152 and 153, are sleeved adjacent to the other ends of said 130

- shafts 150 and 151 and engage the splines 154. The cams 152 and 155 are similarly positioned to their shaft 150 and the cams 153 and 156 are similarly positioned to their shaft 151.
- 5 To the outer face of the frame 21 are fastened a pair of brackets 158 each with the journal bearing 159. The shafts 150 and 151 extend through the brackets 158 and each has fastened thereto the worm wheel 160. A shaft 162 is journaled in each of the bearings 159 and has fastened thereto a worm 163 in mesh with the worm wheel 160. A worm wheel 164 is fastened to each of the shafts 162.
- 10 15 A pair of journal pins 165 are journaled in the frame 21 and each has fastened thereto the worm 166, which is in mesh with its adjacent worm wheel 164. A hand wheel 167 is fastened to each of the pins 165.
- 15 20 A key color cylinder 172 with the metallic sleeve 172^a is fastened to the shaft 173, having the journal ends 174. A pulley 175 having a tapered opening through its hub is provided for one of the journal ends 174.
- 25 30 35 A tapered bushing of which there is a pair indicated with the members 176 having the threaded ends 177 and which are partly separated by the slots 178. A slot 179 extends through the members 176 and the ends 177. Lock nuts 181 are provided for said threaded ends 177. The bushings having the members 176 are located within the tapered openings of the pulleys 175 and 188 to be described to clamp the said pulleys in place on their journal ends and which latter can therefore vary in diameter. The journal end 174 adjacent to the main frame 20 is supported on the rollers 46, and the other journal end 174 is supported on the rollers 128.
- 40 45 50 A receiving cylinder is indicated at 185 with its sleeve 185^a, respectively equal in diameter to 172 and 172^a. The cylinder 185 is fastened to the shaft 186 having the journal ends 187, which shaft and ends are similar to 173 and 174. A pulley 188 equal in diameter to 175 is secured in place by one of the bushings having the members 176. One of the journal ends 187 is supported in its adjacent pairs of rollers 46 and 128.
- 55 60 65 A pin 192 extends from the end frame 20 and has fulcrumed thereon the foot lever 193, which at its front end has formed therewith the foot pedal 194 and at its other end the counter weight 195. A flanged tension roller 196 is journaled on a pin 197, extending from the foot lever 193, adjacent to its front end; and a flanged roller 198 is journaled on the pin 192. A projection 204 with the tooth 205 is formed with the upper edge of the foot lever 193. An endless belt 208 connects the pulleys 88, 175, 188, and the rollers 196, 198. The pin 56 has also fulcrumed thereon the ratchet pawl with the arms 211 and 212. The arm 211 has formed therewith the counterweight 213, and the arm 212 has formed there-
- with the ratchet teeth 215, which engage with the tooth 205. A foot pedal 216 is formed with the said ratchet pawl.
- 65 70 75 80 85 90 95 100 105 110 115 120 125 130 In the guide strips 26 are guided the pair of slide bars 220 having the elongated openings 222 and 223. At the lower end of each of said bars 220 and at their inner faces are journaled the rollers 225. Between the openings 222 and 223 of said bars and adjacent to their inner faces are journaled the rollers 226. To the upper end of each of the slide bars 220 are adjustably connected the journal bearing housings 227. Each of the housings 227 has a shoulder 228 and a projecting lip 229. An elongated opening 230 is formed in each of the lips 229. The shoulders 228 of said housings bear on the top ends of their slide bars 220, and a bolt 231 extends from each of the slide bars through the openings 230, and adjustably clamp the said housings 227 to their slide bars 220. In each of the housings 227 is formed the guide opening 235 for the adjustable journal bearing blocks 236. In the openings in each of the latter are supported a pair of journal bearings with their ball bearing cages 237. A cap 238 is fastened to the top end of each housing 227. An adjusting screw 239 with the hand wheel 240, is in threaded engagement with an opening in the cap 238, and its lower end has connected thereto a flange collar 241 which engages a corresponding opening in the top end of the bearing block 231.
- 100 105 110 115 120 125 130 A cam shaft 246 is journaled in the frames 20 and 21. A pair of cams 247 are fastened to the shaft 246 and coact with the rollers 225 of the slide bars 220. A pin 248 projects outwardly from the end frame 20 and has journaled thereon a sprocket chain wheel 249. An arm 250 has one end fastened to the shaft 249, and an operating handle 251 extends from its swinging end. A pin 252 extends outwardly from the frame 20 and has journaled thereon the sprocket chain wheel 253. A pin 254 extends outwardly from the end frame 20 and has journaled thereon the sprocket chain wheel 255. A sprocket chain wheel 256 is fastened to the cam shaft 246. A sprocket chain 260 contacts with wheels 249, 253, 255 and 256. A shaft 261 has its ends journaled in the roller bearings having the cages 237. A transfer drum 262 is fastened to the shaft 261 and is covered with the sleeve 263 of pliable material, preferably rubber.
- 120 125 130 A pair of slide bars 266 are slidably supported in the guide strips 38 of the frames 20 and 21. Openings 267, 268, 269 and 270 are formed in each of the slide bars 266. To the upper end of each of the slide bars 266 is fastened the bracket 272. A plate 273 with the upturned lip 274 is fastened to the top face of each bracket 272. Longitudinal plates 275 are supported on the plates 273. Guide strips 278 extend up from the plates 273 and slidably support the slide

blocks 279. Journal bearings 280 extend up from the slide blocks 279. Threaded lugs 281 extend up from the slide blocks 279. Adjusting screws 282 extend through the lips 274 and are in threaded engagement with the lugs 281.

An extension 293 with the journal bearings 294 and 295 is provided for one of the slide blocks 279 and has journaled therein the 10 vertical shaft 296, with the squared end 296a. A worm 297 is provided for the shaft 296 and is located between the journal bearings 294 and 295. A shaft 300 is journaled in the journal bearings 280 of the slide blocks 279. 15 To one end of the shaft 300 is fastened the worm wheel 301, which meshes with the worm 297. Three similar supporting brackets 302 are fastened to the shaft 300. Arms 303 are formed with each of the brackets 302. 20 A stiffening shaft 304 connects the brackets 302. A doctor blade support 305 has formed therewith the depending lip 306 and is supported on each of the arms 303. Hook arms 307 extend from each of the brackets 25 302 and from which may be suspended weights. A doctor blade 308 is supported on the support 305. A stiffening plate 309 bears on the doctor blade 308. A cap plate 310 bears on the stiffening plate 309 and bolts 311 clamp the said cap plate 310, stiffening plate 309, doctor blade 308 and the support 305 together.

An ink tank 315 is supported on the longitudinal plates 275. A shaft 316 is journaled 35 in the frames 20 and 21 and has fastened thereto a pair of similar pinions 317. The shaft 316 extends through the openings 267 of the slide bars 266. Similar racks 318 are fastened to the slide bars 266 and mesh with 40 the pinions 317. At one end of the shaft 316 adjacent to the outer face of the frame 21 is fastened the sprocket chain wheel 319. A pin 320 is fastened in the end frame 21 and extends from its outer face. A spur gear 321 45 is journaled on the pin 320. A sprocket chain wheel 322 is fastened to the pinion 321. A sprocket chain 323 connects the wheels 319 and 322. A pin 324 extends from the end frame 21. A hand wheel 325 is fastened to 50 the pinion 324a and both are sleeved on the pin 324. The pinion 324a meshes with the gear 321. A pin 326 extends from the frame 21 and has sleeved thereon the pawl 327 which engages the teeth of the spur gear 321. 55 The steps used in this invention to produce a set of multicolor intaglio cylinders are as follows.

Colored pictures or photographs are photographically reproduced and color separation 60 negatives are made of them, in accordance with the number of colors to be printed. Register marks are placed on the original copies which are transferred while making the color separations. These register marks 65 are used to locate the carbon tissues made

from the color separations, to be described, on the printing cylinders. Next photographic positives are made from the color separation negatives with their register marks. The key color or black positives are now mounted 70 on a glass plate over a layout sheet, forming an arrangement of the sheet to be printed. The mounted positives are next exposed to carbon tissues and are printed thereon. The carbon tissues are afterward exposed to a 75 screen, by which the screen lines are printed thereon. Next the carbon tissues are located upon the key color cylinder conforming with the arrangement of the layout sheet, and attached to the cylinder. The carbon tissues are 80 next developed on the cylinder and the latter is then etched. The key color cylinder is now ready for use. The steps up to this point follow about the usual method used in the previous state of the art. The operator now 85 locates the key color cylinder into the transfer machine, and the configurations and register marks are transferred to the blank receiving cylinder of a diameter equal to that of the key color cylinder, so that the register marks and configurations of the key color cylinder are printed on the receiving cylinder, in a manner to be hereinafter described. The register marks or the outlines or the 90 borders of some of the configurations which have been transferred, are now marked with light scribe marks on the surface of the receiving cylinder, and the latter is next cleaned of ink. The same operation is repeated for 95 each receiving cylinder. A new set of carbon tissues is made from the color separation positives for each color to be printed for each cylinder in the usual manner. The register marks on the carbon tissues are now transferred from the face to the backs of the said 100 carbon tissues, by means of fine pinholes along the vertical and horizontal register lines and through their intersection. The pin holes appearing on the backs of the carbon tissues are next connected by fine pencil lines 105 which will be identical in position with those on the front face of the carbon tissues. The corners of the carbon tissues are cut in inclined lines passing through the apex of each corner of the register marks, which latter are 110 formed with lines preferably at right angles to each other, leaving only a part of said lines. The carbon tissues are next located on the receiving cylinders, and their register marks are brought into register with the corresponding 115 register marks, inscribed on the surface of the receiving cylinders and are attached.

Experience in this art has made known the fact, that when a web press is used for multicolor printing, that the paper printed on, 120 sometimes shrinks in width, when passing from one printing cylinder to the next one, and that the amount of the shrinkage differs between each color printing cylinder. The shrinkage also differs with the various papers. 130

To compensate for these differences, it is necessary to locate the carbon tissues on the receiving cylinders, with their register marks spaced from the register marks on the receiving cylinders to an amount determined by experience. If during the preparation of the carbon tissues any distortion in size has taken place, it will be noted by the operator, when he attempts to locate it upon the receiving cylinder, the register marks of the carbon tissue will be found out of register with those on the receiving cylinder. In such a case the error will have to be corrected with the carbon tissue before taking the next step. Next the carbon tissues are developed on the receiving cylinders in the usual way. Then inspection is made of the register of the register marks of the carbon tissues and the register marks on the receiving cylinders. Should the marks of any of the carbon tissues be found not to be in register with the corresponding marks on the receiving cylinder, the said section of the receiving cylinder with the misplaced carbon tissue is now covered with an acid resisting substance, previous to the etching of the remaining part of the cylinder, and corrected afterwards. In this manner the necessity of the remaking of the whole receiving cylinder is eliminated. While this method of preparing and locating carbon tissues has been found very practical it may be possible to accomplish the same result in other ways without deviating from the spirit of the invention and is not to be considered a limitation thereof. The receiving cylinders are now etched in the usual manner, and their scribe marks are removed. The transferred impressions from the key color cylinder to the receiving cylinders, provide means for making an etching of a flat tint, without the necessity of making a color separation negative and positive therefor. This is accomplished by indicating the border lines of the surface to be etched in tint on the receiving cylinder, cleaning away the ink on the surface of the said cylinder within the border lines, which ink has been transferred from the key color cylinder. Next the cleaned surface on the receiving cylinder is covered with a screened carbon tissue and developed thereon. The marginal surface surrounding the area enclosed by the border lines on said cylinder is next covered with an acid resisting substance, and then the cylinder is etched in the usual way.

If a tone variety instead of a flat tint is to be made, the method will vary in so far, that the approximate position of the etching will be located on the receiving cylinder, and covered with a screened carbon tissue developed thereon, previous to making a transfer in the machine from the key color cylinder.

While making the transfer in the machine, the operator must take care that the trans-

ferred impression of the picture or other object to be etched in this manner, will come in corresponding position with the carbon tissue developed on the receiving cylinder. The ink film obtained during the transfer will act as an acid resistant, and produce thereby a variety of tones during the etching operation.

In making a transfer with the machine, an impression is taken from the key color cylinder which is transferred to the receiving cylinder, by means of a transfer drum, the circumferential length of the impression on the receiving cylinder will equal the circumferential length of the etchings on the key color cylinder, and a short repeat of the same. This repeat will be indicated on the receiving cylinder, by a heavier impression. The repeat must be found in register with the starting point on the receiving cylinder. If this is found to be so, it will prove that the circumferences of the key color and receiving cylinder are equal, and that the transfer operation is correct. Should the repeat however not register with the said starting point, the cause may be an inequality between the cylinders or an error in operating the machine. The error must be located and corrected before other steps are taken. In this manner a check is provided to make the transfer fool proof, also to check the sizes of the cylinders.

To operate the machine (see Figs. 2 and 4) the user first lowers the ink tank 315, by releasing the pawl 327, from the spur gear 321, and then turns the hand wheel 325, by virtue of which the shaft 316 is turned, and the pinions 317 coacting with the racks 318 lower the slide bars 266, and the ink tank 315 is lowered. The latter is then locked in its lower position by the pawl 327.

Next the hand wheel 167, associated with the shaft 150, (see Figs. 2, 3 and 4) is turned, which turns one of the pins 165 with its worm 166. The worm wheel 164 turns with the worm 166 and thereby the worm 163 is turned. The latter through the worm wheel 160 turns the cam shaft 150 having the cams 152 and 155, until the latter are located in their lowest position as indicated in Fig. 2.

Next the key color cylinder 172 is brought into proper position by means of a hand truck, adjacent to the loading bars 135 and 146, with its shaft 172 above the said bars. A pair of the stop pins 149 are placed in position on each loading bar 135, 146 at their outer ends in the openings 149^a, 149^b on opposite sides of the journal ends 174 of the shaft 173 of the key color cylinder 172. Next the said hand wheel 167 is again turned to locate the cams 152 and 155 in their high position, by means of which the loading bars 135 and 146 are swung to a horizontal position, (see Fig. 4). Then the innermost of the placed stop pins 149 is placed in the open-

ing 149° at the other end of each of the loading bars 135 and 146. The journal ends 174 of the shaft 173 of the key color cylinder are rolled to and against the latter stop pin. The outermost of each pair of pins 149 in the openings 149^a in the bars 135 and 146 are now located in the opening 149^c adjacent to the opposite side of the journal ends 174 of the key color cylinder. Next the outer ends of 10 the loading bars 135 and 146 are lowered by means of the hand wheel 167, associated with the shaft 150, and thereby the journal ends 174 of the shaft 173 of the key color cylinder are seated upon the rollers 46 and 128. 15 The pulley 175 is now fastened in place to one of the journal ends 174 of the shaft 173 of the key color cylinder adjacent to front frame 20. The operator by means of the other hand wheel 167 associated with the 20 cam shaft 151, (see Figs. 1, 2, 3, 4) locates the receiving cylinder 185, with the journal ends 187 of its shaft 186, upon the other rollers 46 and 128. Next the pulley 188 is fastened to the journal end 187 of the shaft 186, 25 in line with the pulley 175 and adjacent to the frame 20. The ink tank 315 is now raised to its proper position under the key color cylinder 172, to immerse a portion of the latter in the ink in the said tank. The doctor 30 blade 308 is located with its end bearing on the key color cylinder 172, by turning the shaft 296. This turns the worm 297, and thereby the worm wheel 301 is turned and with it the shaft 300 is swung, which swings 35 the doctor blade 308 in proper position. Weights may be suspended from the hooks 307, to nicely adjust the doctor blade 308 in contact with the key color cylinder 172. By means of the depending lip 306 surplus ink 40 is returned to the ink tank 315. Next the key color cylinder 172 is turned by turning the pulley 175 for the preliminary inking of the key color cylinder 172, and the proper adjustment of the doctor blade, until a satisfactory scrape on the key color cylinder is obtained. The ink used is very slow drying.

The belt 208 is now located in place upon the pulleys 175, 188, 83, 196, and 198. The 50 slide bars 220 are then lowered by turning the operating handle 251, (see Figs. 1 and 3) which turns the sprocket chain wheel 249, and by means of the sprocket chain 260, the sprocket chain wheels 253, 255 and 256 are turned. By 55 this means the shaft 246 is turned, whereby the cams 247 are revolved to their lowest position. The slide bars 220 are now lowered from their high position as indicated in Figs. 1 and 2. The rollers 226 are lowered to the 60 two lifting bars 70. The key color cylinder is now again turned by means of the pulley 175 a number of times, to ink it, and is finally positioned so that the predetermined starting point which usually constitutes a marginal 65 space in the print, is diametrically opposite

to the contact line of the key color cylinder and transfer cylinder. Next the operator adjusts the cam discs 86 to locate their projections 87 in proper position, which is determined by the diameters of the key color cylinder and receiving cylinder, by means of the hand wheel 93^a. 70

Next the operator bears on the foot pedal 194 and thereby tightens the endless belt 208 in place. When the operator bears on the 75 foot pedal 194, the ratchet teeth 215 coact with the tooth 205 of the projection 204 on the arm 211, which locks the foot lever 193 in its tensioned position. To release the foot lever 193 the operator bears on the foot pedal 216, and unlocks the tooth 205 from the ratchet teeth 215. The operator now moves the handle 57, (see Figs. 1 and 3) and through the link 53, the arms 51 and 59 move the lifting bars 70 in position, to seat the rollers 226 80 in the recesses 71 and under the retaining heel 72. This locates the transfer drum 262, in contact with the key color cylinder 172 and the receiving cylinder 185. A final adjustment for the drum 262 is made with the hand 85 wheels 240, through the intervention of the journal bearing blocks 236. The bolt 231 with its elongated opening 230 allows the lateral alignment of the said transfer drum 262. 90

The operator now turns the operating 95 handle 109 (see Fig. 1) which turns the shaft 94, whereby the pinion 96 is turned. The latter turns the pinion 91, which in turn rotates the spur gear 88 and thereby the endless belt 208 causes the pulley 83 to turn, and by means of the belt 208, the pulleys 175, 188, 88, 196 and 198 are turned in unison. The rotation of the pulleys 175 and 188 cause the key color cylinder 172 and the receiving cylinder 185 and the transfer cylinder 262 to 105 turn with the same circumferential speed. The transfer drum 262 bearing equally on the two cylinders will be turned by its contact with the two cylinders 172 and 185.

The key color cylinder 172 carries printing 110 fluid in its etching which comprise the design to be reproduced, and also the register marks. The ink from the key color cylinder is deposited on the transfer drum 262 and in turn is transferred to the receiving cylinder 185. 115

With the shaft 82, the discs 86 are turned and are timed, so that when the receiving cylinder 185 has received a complete transfer and a partial repeat, the cam projections 87 contact with the rollers 78, causing the arms 51, 52 and 59 to swing, and thereby move the lifting bars 70 horizontally. Thereby the rollers 226 are raised out of the recesses 71 and the retaining heels 72, which raises the transfer drum 262 out of contact with the cylinders 172 and 185. The operator next raises the transfer drum 262 in the position indicated in Fig. 4. The operator then bears on the foot pedal 216 to release the tension of the belt 208. Next the pulley 188 is removed 120 125 130

from the receiving cylinder 185. The loading bars 142 and 146^a are raised, and the pins 149 are removed from the inner portion of the said bars and one of them is located at the extreme outer end of each of said bars. The receiving cylinder 185 is now rolled on the journal ends 187 of its shaft 186 toward the stop pins 149 located on the outer ends of the bars 142 and 146^a. Next the other pins at the outer ends of the latter bars are located in place. The loading bars 142 and 146^a are now lowered until the receiving cylinder 185 has been relocated on its hand truck.

5 If more than two colors are to be printed, other receiving cylinders are treated corresponding to the number of colors to be printed.

The adjustable bearing frame 115 which can be moved longitudinally, provides means to adapt the machine to various lengths of key color and receiving cylinders. The length of the transfer drum must be equal to the length of the longest cylinder used. The adjustment of the journal bearing blocks 236 provides means to compensate for variations in the diameters of the key color and receiving cylinders.

After each receiving cylinder is removed from the machine the transfer drum 262 is cleaned. The key color cylinder 172 is finally removed from the machine for use in the printing press (not shown) after all transfers have been made.

25 The construction of the machine may be varied, so that the transfer drum 262, will not simultaneously contact with the key color cylinder 172 and the receiving cylinder 185. In such a case the construction would be modified to the extent that the said transfer drum 262 would first contact with the said key color cylinder 172, and take an impression therefrom, and next said transfer drum would be moved to contact with the receiving cylinder 185, and transfer the impression thereto. The pulleys 175 and 188 and their coacting elements can be eliminated. The rotations of the key color cylinder 172 can be transferred to the transfer drum 262 by rolling contact, and the receiving cylinder 185 can be rotated by rolling contact with said drum, so that the said key color cylinder and receiving cylinder rotate in unison. In this case suitable provision is made to constitute the key color cylinder the driver.

50 Various modifications may be made in the invention and the present exemplification is to be taken as illustrative and not limitative thereof.

Having described our invention what we desire to secure by Letters Patent and claim is:

60 1. In a machine of the character described having an etched cylinder and a blank cylinder journaled therein, the combination of a

transfer drum in rolling contact with said cylinders to transfer an impression from the etched cylinder to the blank cylinder, and means to adjust the transfer drum to different position for cylinders of various diameters. 70

2. In a machine of the character described having an etched cylinder and a blank cylinder journaled therein the combination of a transfer in rolling contact with said cylinders to transfer an impression from the etched cylinder to the blank cylinder, means to bring the transfer drum into contact with the cylinders and means to automatically separate said drum from said cylinders at a predetermined time. 75

3. In a transfer machine of the character described the combination of a main frame and an adjustable bearing frame, said machine having an etched cylinder with journal ends and having a blank cylinder with journal ends, one journal end of each cylinder rotatively supported in the main frame and the other journal end of each cylinder rotatively supported in said adjustable bearing frame, to compensate for cylinders of different lengths. 80

4. In a transfer machine of the character described having an etched cylinder and a blank cylinder rotatively supported therein, the combination of loading bars hinged in the machine for lifting or lowering the cylinders thereof to locate them in the machine or detach them therefrom. 85

5. In a machine of the character described having a key color cylinder and a receiving cylinder rotatively supported therein, the combination of slide bars guided in the machine, rollers journaled to said slide bars, lifting bars adapted to support said rollers with the slide bars located in their lowered position, a cam shaft journaled in the machine, cams fastened to said shaft, said cams adapted to raise and lower said slide bars and a transfer drum adjustably journaled to said slide bars, said transfer drum adapted to contact 100 with both of said cylinders. 105

6. In a machine of the character described the combination of a front frame and a rear frame, means to maintain said frames in place, a bearing frame adjustably supported on said means, four pairs of rollers for the front frame one of each pair on opposite sides of the frame, four pairs of similar rollers for the bearing frame, means to locate the bearing frame in different linear positions, a pair of loading bars oppositely positioned, pinned to said front frame, a pair of loading bars oppositely positioned, pinned to the bearing frame, means to support and swing the outer ends of the loading bars to different positions, said machine having a key color cylinder with a shaft having journal ends adapted to roll on a loading bar of the front frame and the bearing frame and adapted to be seated on the rollers connected there- 115 120 125 130

to, said machine having a receiving cylinder with a shaft having journal ends adapted to roll on the other loading bar of the front frame and the bearing frame and to be seated 5 on the rollers connected to the front frame and bearing frame, a slide bar adjustably supported in the front frame, a second slide bar adjustably supported in the rear frame, and a transfer drum journaled to the slide bars 10 adapted to contact with said cylinders.

7. In a machine of the character described the combination of a front frame and a rear frame, a bearing frame adjustably supported between said frames, rollers associated with 15 the front frame, rollers associated with the bearing frame, a pair of loading bars oppositely positioned pinned to the front frame, a pair of loading bars oppositely positioned pinned to the bearing frame, means to support and 20 swing the outer ends of the loading bars, said machine having a key color cylinder with a shaft having journal ends adapted to roll on a loading bar of the front frame and a loading bar of the bearing frame and to be 25 seated on the rollers associated therewith, said machine having a receiving cylinder with a shaft having journal ends adapted to roll on the other loading bars and to be seated on the rollers associated therewith, a transfer drum 30 adjustably supported in the machine and adapted to contact with the cylinders, means to simultaneously turn said cylinders, other

means to lock said means in operative position and automatic means to space said transfer drum from said cylinders after a predetermined circumferential travel of the drum. 35

8. In a machine of the character described having an etched cylinder and a blank cylinder journaled therein, the combination of a transfer drum adjustably journaled in the machine in rolling contact with both of said cylinders, means to simultaneously turn the cylinders, the drum simultaneously rotating with said cylinders by reason of its rolling contact therewith and means to space the transfer drum from the cylinders after a predetermined amount of rotation of the latter to produce a repeat on the blank cylinder. 40

9. In a machine of the character described having an etched cylinder and a blank cylinder journaled therein, the combination of a transfer drum journaled in the machine in rolling contact with both of said cylinders, means to simultaneously turn the cylinders, the drum simultaneously rotating with the cylinders, an ink tank adjustably located adjacent to the etched cylinder, means to locate said ink tank to immerse the etched cylinder in the ink in said ink tank and a doctor blade 55 adjustably associated with said ink tank. 60

In testimony whereof we affix our signatures.

ARTHUR DULTGEN.
